US00D602064S

(12) **United States Design Patent**
Mitsui et al.

(10) **Patent No.:** US D602,064 S
(45) **Date of Patent:** ** Oct. 13, 2009

(54) **DATA DISPLAY**

(75) Inventors: **Sei Mitsui**, Suita (JP); **Yasushi Tanijiri**, Osakasayama (JP); **Hiroshi Yamaguchi**, Suita (JP)

(73) Assignee: **Konica Minolta Holdings, Inc.**, Chiyoda-Ku, Tokyo (JP)

(**) Term: **14 Years**

(21) Appl. No.: **29/297,223**

(22) Filed: **Nov. 7, 2007**

(30) **Foreign Application Priority Data**

May 11, 2007 (JP) 2007-012418
May 11, 2007 (JP) 2007-012419

(51) **LOC (9) Cl.** **14-03**

(52) **U.S. Cl.** **D16/300; D14/126**

(58) **Field of Classification Search** ..... D14/125-134, D14/239, 371, 136, 374-377, 440, 450, 448, D14/336, 342; 312/7.2; 348/836, 838, 180, 348/184, 325, 739; 341/12; 248/917-924, 248/465; 345/104, 133, 156, 168, 87, 173; 720/605, 669, 600, 655; 369/99, 197; 455/344, 455/347; D21/329, 515, 577, 622, 333, 433, D21/448, 452, 450, 331; D6/477, 479, 300; 273/148 B; 446/484, 175, 356; D10/15, D10/26; D16/300-340; 351/158, 41

(57) **CLAIM**

the ornamental design for a data display, as shown and described.

DESCRIPTION

FIG. 1 is a perspective view of a data display showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view showing a data display which is folded;

FIG. 9 is a perspective view of a data display showing a second embodiment of our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a perspective view showing a data display which is folded.
